UNITED STATES PATENT OFFICE.

WILLIAM E. HIGHFIELD, OF PHILADELPHIA, PENNSYLVANIA.

MACHINERY FOR CHANGING THE ANGLE OF THE FLANGES OF ANGLE-BARS.

SPECIFICATION forming part of Letters Patent No. 249,352, dated November 8, 1881.

Application filed May 5, 1881. (No model.)

To all whom it may concern:

Be it known that I, WILLIAM E. HIGHFIELD, a citizen of the United States, residing in Philadelphia, Pennsylvania, have invented certain 5 Improvements in and Machinery for Changing the Angles of the Flanges of Angle-Bars, of which the following is a specification.

The object of my invention is to effect the rapid and accurate spreading of angle-iron 10 bars—that is to say, the changing of the angle of the flanges as demanded by the position of the bar in the ship or other structure of which it is to form part. This object I attain in the manner which I will now proceed to describe, 15 reference being had to the accompanying drawings of the machine which I employ in carrying out my invention.

Figure 1, Sheet 1, is a side view of the machine; Fig. 2, a transverse section on the line 20 1 2; Fig. 3, Sheet 2, a longitudinal section of Fig. 1; Fig. 4, the same with the parts in a different position; Figs. 5 and 6, Sheet 1, diagrams illustrating the character of the work 25 performed by the machine; and Fig. 7 a diagram, showing the defect of the usual method.

In building iron vessels or other structures having angle-iron frames, it becomes necessary to spread or change the angle of the flanges.

The common method of performing this operation is to secure one of the flanges of the bar to a bed-plate or casting and then hammer the other flange against a suitable templet or templets. This mode is objectionable, partly on account of its tedious and expensive character, but principally because it results in the production of a curved or hollow flange, as in Fig. 7, the angle being more acute at and near the corner or point of junction x than it is at other parts of the flange, owing to the greater 30 thickness of metal at said point x , and the consequent greater difficulty of bending the flange at this point by hammering. Owing to this curved or hollow shape of the flange it fails to afford a firm seat for a plate or bar which is 35 riveted thereto, and a structure in which the angle-irons are used must, on this account, always be more or less defective.

In carrying out my invention I discard the plan of hammering the flange, and effect the 40 operation by means of rolls in the manner illustrated in the drawings, in which—

A A' and B B' represent four conical rolls carried by short shafts a a' and b b' , the pair of rolls A A' being adapted to one flange, y , of the angle-bar, and the other pair of rolls, B B', being adapted to the other flange, y' , of the same. Each roll-shaft is carried by two boxes, the outer box, d , of each shaft being pivoted to the opposite side frames, D, of the machine, and the inner boxes, d' , of the shafts having projecting lugs or pins adapted to slots d'' in said side frames.

Power is applied to the shafts a and b , and is transmitted therefrom to the shafts a' and b' through the medium of suitable bevel-gearing, 65 as shown, so that the rolls A B are caused to revolve in one direction and the rolls A' B' in the opposite direction. Power may be applied to the shafts a and b in various ways, the means shown in the drawings being a horizontal driving-shaft at the base of the machine, operating in conjunction with suitable bevel-gearing and with vertical and horizontal transmitting-shafts e and f .

One of the vertical shafts, e , carries a cone-pulley or drum, g , a belt passing round the same and round a similar cone-pulley on a short vertical shaft, h , which is provided with a worm, i , the latter gearing into a worm-wheel, k , on a central longitudinal shaft, m , adapted 70 to suitable bearings on the frame of the machine. The shaft m carries eccentrics n , which act upon two pairs of sliding yokes, p , adapted to guides on the side frames, D, one pair of said yokes being connected by rods s to the 75 boxes d' of the shafts a a' , and the other pair of yokes being connected by similar rods to the boxes d' of the shafts b b' .

The operation of the machine is as follows: The angle-bar is drawn from the furnace by 90 means of tongs or other suitable drawing mechanism, and the end of the bar is introduced between the rolls while the latter are in the position shown in Figs. 1 and 3, the faces of the rolls A A' being at right angles to those of the 95 rolls B B', and the yokes p being at the limit of their upward movement. As the bar is fed through the rolls, however, the latter are depressed by the action of the eccentrics n on the yokes p , and a consequent change in the angle 100 of the pairs of rolls in respect to each other is effected, as shown in Fig. 4, thus resulting in

the desired spreading or changing of the angle of the flanges $y y'$ of the angle-bar. The spreading of the bar is effected gradually or abruptly in accordance with the gradual or abrupt depression of the rolls; hence this result is governed by the speed of the eccentric-shaft m in respect to the speed of the shafts $a a'$ and $b b'$, so that by a proper adjustment of the belt on the cone-pulleys g the spreading of the flanges can be regulated as desired.

It is advisable in most cases to make the worm i loose on the shaft h , and to provide said shaft with a device for clutching the worm to or releasing it from the shaft, so that any desired length of the bar can be allowed to pass between the rolls before throwing the shaft m into gear and commencing to depress said rolls and spread the bar.

Suitable indicators may be employed in connection with the shaft m and shafts $a a'$ and $b b'$, in order that the attendant may readily observe and govern the movements of the shafts and the character or extent of the change in the angle of the flanges of the bar.

The slots d^2 in the frames D are such that the rolls $A A'$ and $B B'$ preserve the same longitudinal relation to each other at the point w , irrespective of changes in the vertical position and in the angle of the rolls, so that each flange of the angle-bar is always confined by the rolls throughout its entire width; hence the flanges of the finished bar present a uniform flat bearing throughout and afford a firm seat for plates or bars that may be riveted thereto.

Although I have shown cone-wheels as the means of varying the speed of the shaft m in respect to the speed of the roll-shafts, change-wheels or frictional speed-changing devices may be used, and the eccentrics, yokes, and

rods, whereby the shaft m is caused to control the position of the roll-shafts, may be replaced by other connections, and in some cases the rolls may retain a fixed vertical position, changes in the angle of the rolls being effected by elevating or depressing the outer ends of the roll-shafts.

I claim as my invention—

1. The mode herein described of changing the angle of the flange of angle-bars, said mode consisting in passing the bar between two pairs of rolls, which confine the opposite flanges of said bar, and gradually changing the angle of the pairs of rolls in respect to each other as the bar passes between them, as set forth.

2. The combination of the rolls $A A'$ and $B B'$ and their shafts with pivoted boxes d for said roll-shafts, as set forth.

3. The combination of the side frames, D , having slots d^2 , the rolls $A A'$ and $B B'$, and their shafts $a a'$ and $b b'$, the pivoted boxes d , and the boxes d' , having lugs or projections adapted to the slots d^2 , as set forth.

4. The combination of the rolls $A A'$ and $B B'$ and their shafts with the shaft m , having eccentrics n , the yokes p , and connecting-rods s , as set forth.

5. The combination of the rolls $A A'$ and $B B'$, the controlling-shaft m , and devices, substantially as described, whereby the speed of the said shaft m in respect to the roll-shafts may be varied, as set forth.

In testimony whereof I have signed my name to this specification in the presence of two subscribing witnesses.

WILLIAM E. HIGHFIELD.
